CLAIM

The ornamental design for a network video recorder faceplate, as shown and described.

DESCRIPTION

FIG. 1 is a left front perspective view showing our new design for a network video recorder faceplate;

FIG. 2 is a right front perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side view elevational view thereof, and,

FIG. 8 is a right side elevational view thereof.

The broken lines are included for the purpose of illustrating portions of the network video recorder faceplate and form no part of the claimed design.
